UNITED STATES PATENT OFFICE.

CHARLES BENJIMAN KAVANAUGH, OF LITTLE ROCK, ARKANSAS.

WASHING MACHINE.

Application filed August 20, 1921, Serial No. 493,963. Renewed May 26, 1923.

To all whom it may concern:

Be it known that I, CHARLES BENJIMAN KAVANAUGH, a citizen of the United States, residing at Little Rock, in the county of 5 Pulaski and State of Arkansas, have invented certain new and useful Improvements in Washing Machines, of which the following is a specification, reference being had to the accompanying drawings.

10 This invention relates to washing machines and has for its object to provide a washing machine capable of imparting a rubbing action to the clothes during the revolution of the drum and agitator.

15 It is another object of the invention to provide a washing machine of this character including a rotatable drum and a rotatable agitator arranged to rotate in opposite directions and at different speeds, the shaft 20 of the agitator being concentric to both the agitator and the drum.

It is also an object of the invention to provide a washing machine of this character including a main driven shaft, said shaft 25 carrying an agitator and rotatably supporting a drum, the drum surrounding the agitator, and means carried by the end of the shaft for rotating the same and the agitator, and means carried by the drum and operated by the operating means of the shaft for 30 rotating the drum in the opposite direction to that of the agitator and the shaft, but on the shaft.

It is still a further object of the invention 35 to provide a washing machine of this character embodying a drum, and an agitator rotatably mounted within the drum, the reservoir having an internal gear connected thereto, the agitator having an external gear connected thereto, and means carried by the washing machine and disposed between said gears for rotating the gears simultaneously in opposite directions.

With these and other objects in view, the 45 invention consists in the improved construction and arrangement of parts to be hereininafter more particularly described, fully claimed and illustrated in the accompanying drawings, in which:—

50 Figure 1 is an end elevation of a washing machine constructed in accordance with an embodiment of the invention,

Figure 2 is a transverse sectional view of the structure shown in Figure 1,

Figure 3 is a section taken on the line 55 3—3 of Figure 1, and

Figure 4 is a fragmentary top plan view of the structure shown in Figure 1, the cover of the machine being removed.

Referring to the drawings, 4 designates a 60 tank having a rounded bottom 5 and a cover 6. Supports 7 are secured to the ends of the tank, each support extending from the upper edge to a point considerably below the bottom of the tank. That portion of each of the supports adjacent the bottom of the tank is provided with an extension 8, the extension of each support extending toward each other. Brackets 8^a are carried by the extensions, the brackets being arranged 65 to engage the bottom of the tank.

Disposed within the tank 4 is a relatively 70 large drum 10 of conventional construction, said drum being made preferably of wood and having a series of perforations for the 75 passage of water therethrough. The interior of the drum 10 is provided with a plurality of spaced ribs 11 which extend inwardly of the drum. The end 12 of the drum is provided with an opening 13. A 80 portion of the drum is opened to permit clothes to be disposed therein, said opening being closed by a cover 12^a which may be of any conventional construction. A bearing member projects from one edge of the cover 85 and is adapted to engage the inner surface of the drum, the opposite end of the cover being engaged with pins which project from the sides of the drum adjacent the opening.

A bearing member 14 is disposed over the 90 opening 13 and is provided with a clutch member 15. The end 17 of the drum is provided with an opening 18 which registers with the opening 13. A relatively large opening 19 is formed in the end 20 of the 95 tank, said opening being positioned substantially centrally of said end. A stuffing box 21 is secured to the outer face of the end 20, said stuffing box registering with the opening 19, a bushing 22 being disposed within the stuffing box.

In order to rotate the drum, a sleeve 23 is rotatably mounted within the bushing 22, one end of said sleeve having a plate 24 connected thereto, while the opposite end of the sleeve has a clutch member 25 formed thereon by reducing said end portion of the sleeve. By this novel arrangement, the clutch members 15 and 25 100 105

are adapted to engage each other to permit rotation of the agitator with the sleeve and also to facilitate assembling of the machine. Connected to the plate 24 exteriorly of the tank 5 is a relatively large gear 26, said gear having internal teeth 27 and a semi-circular slot 28, which is disposed adjacent the periphery of the disc. The internal gear 26 forms the operating gear for the drum, the method of operation to be described hereinafter.

A main driven shaft 29 is provided, said shaft being adapted to extend through the bore of the sleeve 25, said sleeve thereby providing a bearing for the shaft. The opposite end of the shaft is disposed in a bearing 30 which is carried by the end 31 of the tank. The opening 18 of the drum being adapted to receive the shaft to rotatably support said ends of the drum. The opening 13 of the end 12 of the drum is likewise adapted to receive the opposite end portion of the shaft to provide a support for the end 12 of the drum. It is of course obvious that the opening in the bearing member 14, clutch member 15, and the sleeve 23, is sufficient to provide a passage for the shaft 29. An agitator 32 is mounted on the shaft 29 within the drum 10, said agitator having flanges 33 disposed at its ends, while extending longitudinally of the agitator and supported by the flanges is a plurality of ribs 34 which are disposed at spaced intervals circumferentially. The agitator 32 is secured to the shaft and adapted to rotate therewith, while the ends of the drum are rotatable on the shaft. The end 35 of the shaft is provided with a key way 36 and adapted to receive a gear 37, a key 38 being disposed in the key way 36 for connecting the gear to the shaft. It will be noted that the gear 37 is disposed within the gear 26 and in annular spaced relation to the internal teeth 27 of the gear 26. As the gear 26 is carried by the sleeve 23, it is free to rotate independently of the gear 37 and shaft 29.

To operate the drum and agitator, a bearing 39 is carried by the end 20 of the tank exteriorly thereof, while secured to the extensions 8 of the supports 7 is a bracket 40 having a bearing 41 positioned centrally thereof, said bearing being adapted to register with the bearing 39. A shaft 42 is journaled in the bearings 39 and 40 and is adapted to support a gear 43. The gear 43 is adapted to be disposed between the teeth of the gears 26 and 37. The length of the gear 43 is greater than the thickness of the gears 26 and 37 so that one end portion of the gear 43 projects beyond the internal and external gears 26 and 37. Secured to the lower portion of the support 7 substantially beneath the bracket 40 is a bracket 44 having registering bearings 45 adapted to receive a

shaft 46. Mounted on the shaft is an arm 47 of a segmental gear 48, the segmental gear being adapted to mesh with the projecting portion of the gear 43, so that rotation of the gear 43 will cause rotation of the internal and external gears 26 and 37. It will be noted that the shaft 42 of the gear 43 extends through the slot 28 of the gear 26 so as to permit rotation of said gear. The ends of the slot 28, however, serve as stops to limit the rotation of the gear by engaging the end portion of the shaft 42. One end portion of the arm 47 projects below the shaft 46 and is provided with an opening 49 to which any suitable means may be connected for oscillating the arm 47.

In the operation of the device, power is transmitted to the gear 48 through the medium of the arm 47 which causes rotation of the gear 43. This gear in operation meshes with the internal and external gears 26 and 37, and causes rotation of the internal gear in one direction and rotation of the external gear in the opposite direction. Corresponding movement is imparted to the drum and agitator, thereby rotating the reservoir and agitator in opposite directions. In view of the fact that the inner surface of the drum and exterior surface of the agitator are provided with projecting ribs, a rubbing action will be produced which will remove the dirt from the clothes passing between the agitator and the drum and thereby assure thorough washing of the clothes by treating the clothes the same as if the old form of hand wash board were used, and doing the work in a more efficient manner without damaging the clothes.

An important feature of the operating mechanism for the drum and agitator is that the slot 28 may be of various lengths according to the amount of rotation desired for the drum. It may be semi-circular, segmental, or extended to a point almost entirely around the gear 26, so that a complete revolution of the reservoir is possible if desired. In the present instance, however, the slot is arranged for oscillating movement or a half revolution of the reservoir to a whole revolution of the agitator, and the novel arrangement of the gear 48 permits any means to be applied thereto for operating the device either by motive power or manually. This novel construction, in view of its simplicity and compact arrangement, may be incorporated in the conventional forms of washing machine tanks and drums now in use, and treats the clothes the same as if a hand wash board was used, without requiring physical strain on the part of the operator.

What is claimed is:

1. A washing machine of the character described comprising a tank, a bearing sleeve and clutch member rotatably mounted in one

wall of the tank, a shaft extending through said bearing and having one end portion mounted in the opposite wall of the tank, an agitator carried by the shaft, a drum surrounding the agitator and rotatably mounted on the shaft, a clutch member carried by the drum for engagement with the first mentioned clutch member, an internal gear carried by the bearing member exteriorly of the tank, an external gear carried by one end of the shaft, said external gear being disposed inwardly of the internal gear, and means disposed between said gears for simultaneously rotating said gears in opposite directions.

2. A washing machine of the character described comprising a support and tank, a shaft mounted in said tank, an agitator carried by the shaft, a reservoir freely

mounted on the shaft, an internal gear connected to the drum, said gear being disposed exteriorly of the tank, an external gear connected to the shaft, said external gear being disposed within the internal gear, said internal gear having a slot positioned between the teeth of said internal gear and the external gear; a shaft extending through said slot and journaled in the support of the tank, a driving gear carried by said shaft for simultaneously rotating the internal and external gears, the shaft of said driving gear being adapted to limit movement of the internal and external gears upon engagement of the shaft of the driving gear with either end of said slot.

In testimony whereof I hereunto affix my signature.

CHARLES BENJIMAN KAVANAUGH.
